Term of patent 14 years

(Cl. D92—17)

FIG. 1

FIGURE 2

FIGURE 1 is a plan view of a hard surface floor covering, showing my new design.

FIGURE 2 is an enlarged view of a portion of a repeating unit of the hard surface floor covering or similar article shown in FIGURE 1.

A unit is enclosed within the broken lines on the drawing, which unit is repeated in regular succession as indicated by the extension beyond the unit boundaries.

I claim:

The ornamental design for a hard surface floor covering or similar article, substantially as shown and described.
